IRRIGATION SIGNAL LAMP

Wilfred Cline, 475 Crummer Lane, Reno, Nev., and
Ray V. Cline, Bishop, Calif.
Filed Aug. 21, 1962, Ser. No. 218,344
2 Claims. (Cl. 340—244)

This invention relates to a signal lamp and is more particularly concerned with a signal lamp for use in connection with agricultural irrigating systems.

In the art of irrigating agricultural lands, it is common practice to establish a plurality of parallel furrows extending longitudinally of a field, between which crops are planted, a primary trench extending transverse and communicating the furrows at one end of the field and a secondary trench extending transverse and communicating with the furrows at the other end of the field.

Water from a suitable source is introduced into the primary trench and flow is continued until the furrows and the secondary trench are flooded. When the secondary trench is flooded, it is known that the entire field has been irrigated and the supply of water is shut off.

It is often necessary or desirable to irrigate in the above manner at night. The reasons for irrigating at night are: first, less evaporation occurs in the cool of the night and results in a considerable saving of water; second, by irrigating at night, the fields are maintained in workable condition during the day, that is, in a condition which makes it possible for laborers and the like to move about in the fields and to tend to the crops during the daylight hours.

Night time irrigation has several material drawbacks. It requires that the person overseeing the irrigating operation stay at the field for many hours during the night, watching and tending to the irrigating operation. This is extremely unsatisfactory and unpleasant, as the nights are often extremely cold and the hours of waiting are extremely long and tiresome.

Oftentimes, the overseers of such operations fall asleep or forget to turn off the water or, to avoid staying out of doors, attempt to calculate when it should be turned off, with the result that over-flooding occurs, and much water is wasted. In arid and semi-arid country, where water is rationed, the results of a person exceeding his allotment of water creates many serious consequences.

The expense of hiring competent persons to work nights, irrigating, is substantial and is avoided by small and less prosperous farmers and ranchers whenever possible.

An object of the present invention is to provide a signal lamp adapted to be positioned at the downstream end of an irrigating system, which lamp is illuminated when the irrigating system is flooded.

Another object of this invention is to provide a lamp of the character referred to which is a portable, battery operated, unitary construction and is such that it can be easily and conveniently moved from place to place, or stored, as circumstances require.

Another object of this invention is to provide a signal lamp of the character referred to which is of considerable vertical extent so that it can be viewed or seen from a distant point, above the crops.

Still another object of our invention is to provide a signal lamp of the character referred to that radiates a signal light uninterruptedly in all directions above the horizontal plane in which the lamp occurs.

Another object of our invention is to provide an agricultural signal lamp of the character referred to which is rugged and durable and which is neat and compact.

A feature of our new signal lamp is the provision of a

2

simple trouble-free, non-fouling float-controlled switching means.

Another feature of our new signal lamp is the provision of a novel combination base and orienting means, 5 which means enhances the stability of the construction and serves to facilitate orienting or positioning the float of the float-controlled switching means.

Still another feature of our invention is to provide a signal lamp having an elongate, vertically-disposed column to project upwardly from the base and at the upper 10 end of which an electric lamp is arranged.

It is another feature to provide a column as set forth above which is tubular and in which the float-controlled switching means is arranged.

Yet another feature of this invention is to provide a signal lamp of the character referred to wherein the column is sectional and the sections are telescopically engaged, whereby the vertical extent of the column can be varied as circumstances require.

20 Yet another object of this invention is to provide anchoring means on the base and engageable in the earth.

The various objects and features of our invention will be fully understood from the following detailed description of typical preferred forms of our invention, throughout which description reference is made to the accompanying drawings, in which:

FIG. 1 is an isometric view of a typical irrigating system, with a signal lamp as provided by the present invention related thereto;

FIG. 2 is a longitudinal sectional view of our new lamp;

FIG. 3 is an elevational view of another form of signal lamp provided by the present invention; and

35 FIG. 4 is an isometric view of a portion of the construction shown in FIG. 3, with portions broken away to better illustrate the details of construction.

The irrigating system A illustrated in FIG. 1 of the drawings is a typical system involving a plurality of parallel, elongate, furrows 10, a primary trench 11 extending transverse and communicating with the several furrows 10 at one end of the furrows and a secondary trench 12 extending transverse and communicating with the other ends of the furrows.

40 45 Water from a suitable supply, as for instance, a pump 13, is introduced into the primary trench 11. The water flows along the trench 11 and into and along the furrows 10 communicating therewith and thence into the secondary trench 12, as indicated by the character W in the drawings.

When the trench 12 is flooded, throughout its longitudinal extent, to a predetermined depth, all furrows are flooded and the entire field in which the system is arranged is properly irrigated. When this condition is reached or attained, the water supply is shut off.

It is not infrequent that an irrigating system such as set forth above, is several hundreds of yards long and several hundreds of yards wide. When irrigating systems are of such size, it is impossible, at night, to see to 60 what extent the water has flooded the system and to determine when the water supply is to be shut off, without waiting at the secondary trench until the desired condition is reached, and then, traveling back to the water supply, to shut it off.

65 It is impossible or impractical to avoid this procedure by timing or metering the flow of water, since the volume of water required to completely irrigate, especially in large systems, varies widely from day to day as a result of variations in the humidity of the soil and its ability to absorb water. That is, the amount of moisture in the soil on any one particular day and the resulting amount of water

which is required to saturate and flood the soil, being controlled by such variables as the temperature of the soil, the temperature and humidity of the air and the size, extent and nature of the plant life growing therein, cannot be accurately predicted.

Further, the rate at which such a system is flooded must often be controlled and varied to control and vary the effective depth of irrigation. Quick flooding results in shallow irrigation, suitable for small, young plants, whereas slow flooding results in deep watering or irrigation, suitable for mature, deep-rooted plants.

As stated above, irrigation is most frequently carried on in the cool of the night when less evaporation takes place and so that the fields will be workable during the following daylight hours.

The signal lamp L that we provide is adapted to be arranged in the secondary trench 12 of the irrigating system A and is such that when the trench 12 is flooded to a predetermined depth, the lamp is energized and sends a light signal, which signal can be seen from a remote place and inform the person overseeing the irrigating operation that irrigation is completed and that it is time to shut off the water supply.

With our new signal lamp, it is possible for one person to oversee the irrigating of several fields, at night, from a position remote from the fields, for instance, from a pump house or even from a dwelling house on the farm or ranch.

In the form of the invention shown in FIGS. 1 and 2 of the drawings, the lamp L includes a base B, a column C projecting upwardly from the base, an incandescent lamp or light bulb D at the upper end of the column C, a power supply means E for the lamp and a float-controlled switching means F controlling the supply of current from the means E to the bulb D.

The signal lamp L further includes a suitable housing G at the upper end of the column C and in which the lamp D is mounted and housed, and a suitable anchoring means H carried by the base and engageable in the earth to enhance the stability of the construction.

The base B is a simple sheet metal unitary structure having a substantially flat triangular-shaped base plate 15 and side walls 16 coextensive with and projecting upwardly from two sides of the base plate. The base plate is adapted to engage and rest on the bottom surface of the trench 12 of the irrigating system A and to establish a flat, clean, upwardly-disposed flooding surface 17. The side walls 16 serve to shore up the soil defining the adjacent sides and/or end of the trench 12, and to prevent excessive dirt from flowing onto and across surface 17.

With the base B shown in FIG. 1 of the drawings, it is possible to set the base into a side of the trench 12 so as not to obstruct the flow of water in and through the trench and so as to enhance the stability of the lamp construction.

In practice, suitable stakes 18, establishing the anchoring means H, can be fixed to the sides of the base, to project downwardly therefrom and into the earth to anchor the construction in fixed position.

The column C is a simple, straight, vertically-extending tubular member formed of steel conduit, or aluminum or plastic tubing. The lower end portion of the column is engaged in the inside rear corner of the base, defined by the base plate 15 and side walls 16 and is fixed therein or thereto as by welding. The lower end of the column opposes the base plate 15 and is provided with a forwardly-disposed lateral opening 19 to admit the entry of water flowing across the surface 17 of the base plate, into the lower end of the column.

The housing G for the lamp D at the upper end of the column C includes an upwardly-opening sheet metal or plastic cup 20 having threads 21 about its rim portion and a central downwardly-extending tubular neck 22, in which the upper end portion of the column C is

slidably engaged. A suitable set screw 23 is carried by the neck to engage the column and to hold the cup in fixed position thereon.

The housing G further includes a downwardly-opening cup-like insert 24 press fitted into the cup. The insert has a central threaded socket opening 25 formed therein and in which the base 26 of the incandescent lamp D is engaged. A central contact 27 for the lamp D is carried by the insert through or by means of a suitable insulated mounting means 28.

In addition to the foregoing, the housing G further includes a downwardly-opening, semi-spherical or dome-shaped glass or plastic lens 29, threadedly engaged about the upper rim portion of the cup and enclosing the lamp D and the interior of the cup.

The power supply means includes a cell or battery box 30 fixed to and projecting from the lower end portion of the column, above the base and in which a suitable electric cell 31, or a battery of cells, is arranged.

The box 30 is fixed to the column as by welding and is provided with an opening at one end to register and communicate with a suitable opening in the column C and through which the electric lines, connecting the cells, switching means and lamp, extend.

The switch F includes an insulated carrier 32 engaged in the lower end portion of the column, a pair of vertically-disposed parallel contact posts 33 and 34 carried by the carrier and projecting from the upper and lower ends thereof, a float 35 arranged in the lower portion of the column, below the carrier to normally engage and stop upon the base plate 15 of the base B, a stem 36 projecting upwardly from the float and a contact plate 37 at the upper end of the stem and adapted to engage and bridge across the lower ends of the posts 33 and 34, when the float is floated and the plate 37 is elevated thereby.

A first electric line 40 extends from the contact 27, or the mounting means 28 therefor, downwardly through the column C and into the box 30 where it establishes contact with one pole of the cell 31. A second line 41 extends from the other pole of the cell or battery of cells, in the box 30, downwardly through the column and connects with the upper end of the post 33. A third line 42 extends from the upper end of the post 34, upwardly through the column C, into the cup at the upper end of the column and connects with the insert 27, which insert establishes the ground contact for the base of the lamp D threadedly engaged therein.

With the set up set forth above, it will be apparent that a circuit is established which circuit is under control of the float-controlled switch F and that the lamp remains unenergized until the float-controlled switch is closed by flotation of the float and resulting elevation of the contact plate, which occurs when the trench 12, in which the signal lamp is arranged, is flooded.

In the form of the invention shown in FIGS. 3 and 4 of the drawings, the base B' is established by a simple, flat, disc-shaped plate 15' defining a flat, upwardly-disposed flooding surface 17'.

The column C' in this second form of the invention is sectional, having a lower outer tubular section 50 and an upper tubular section 51 slidably engaged in the lower section 50. The lower end portion of the lower section 50 is slidably engaged in a central downwardly-extending tubular collar 52 formed integrally in the base plate 15'.

Adjacent the top surface 17' of the base plate 15' and through which water, flowing across the plate, can enter the lower section of the column.

The upper end of the lower section 50 of the column C' is provided with a chuck-type locking means 53 to facilitate gripping and holding the upper section 51 of the column C' in fixed position relative to the lower section 50.

The switch F' in this second form of the invention, like the switch F in the first form of the invention, is engaged within the lower portion of the column C' and includes

like elements. The switch F' distinguishes from the switch F in that the plate 37' is pivotally carried by the lower end of the contact 33' and is adapted to be engaged and pivoted upwardly and into contact with the post 34', by the stem 36' projecting upwardly from the float 35', arranged in the lower end of the column, when said float is floated and elevated.

The anchoring means H' in the second form of the invention, now under consideration, comprises a single elongate, vertical stake 18' established by a flattened extension or continuation of the lower section 50 of the column C', and projecting downwardly from the plate 15'.

The power supply means E' in this second form of the invention consists of a tubular battery case 30' fixed to and projecting upwardly from the upper end of the upper section 51 of the column C'. The lamp D' is engaged in the upper end of the case 30' and is covered or shielded by a semi-spherical or dome-shaped lens threadedly engaged about the upper end of the case 30'.

It will be apparent that the means E' is in the nature of a conventional flashlight mounted or fixed to the top of the column C' and provided with a special lens. In accordance with normal flashlight construction, the means E' can be provided with a suitable thumb-operated switch, indicated at 54, which switch is connected in parallel with the switching means F' at the lower end of the column C', by suitable lines 55 and 56 extending longitudinally through the column C'.

With the second form of the invention described above, it will be apparent that when the construction is being transported or stored, the over-all longitudinal extent of the construction can be materially reduced by telescopically engaging the upper section 51' of the column C into the lower section 50 thereof and that the switch 54 can be opened, thereby preventing draining of the batteries, as might occur by accidental closing of the switch F', as when the structure is laid down, or the like.

Having described only typical preferred forms and applications of our invention, we do not wish to be limited or restricted to the specific details herein set forth, but wish to reverse to ourselves any modifications or variations that may appear to those skilled in the art and fall within the scope of the following claims.

Having described our invention we claim:

1. A signal lamp of the character referred to including, a base having a flat horizontally-disposed ground engaging base plate defining a flat upwardly-disposed flooding surface, an earth-engaging stake fixed to and depending from the base, an elongate vertically-disposed column fixed to and projecting upwardly from the base, an electric lamp at the upper end of the column, a power supply means for the lamp including a battery case fixed to and carried by the column in spaced relationship above the base, an electric cell within the case, and a float controlled switch carried by the column to occur adjacent the flooding surface of the base and elongate flexible conductor lines extending between and connecting the cell, switch and lamp, said switch being operable to control the flow of current between the lamp and the cells, said

5 column including a lower tubular section fixed to the base and projecting upwardly therefrom, an upper tubular section slidably engaged in the lower section and projecting upwardly therefrom and carrying the lamp at its upper terminal end, and manually operable lock means on the lower section to hold the upper section in fixed position relative to the lower section, said lower tubular section having a laterally opening flow passage adjacent the flooding surface of the base, said float controlled switch being arranged within the lower portion of said section and including a vertically-shiftable float within the section to normally occur adjacent the base and said flow passage, said conductor lines extending longitudinally through the column, said base plate having an upwardly projecting soil retaining side wall about a portion thereof, said side wall serving to prevent the flow of soil adjacent the outer side of said side wall, onto and across the flooding surface.

2. A signal lamp of the character referred to including, 20 a base having a flat, horizontally disposed ground engaging base plate defining a flat upwardly disposed flooding surface, an earth engaging stake fixed to and depending from the base, an elongate vertical disposed tubular column fixed to and projecting upwardly from the base, an electric lamp at the upper end of the column, a power supply means for the lamp including a battery case fixed to and carried by the column in spaced relationship above the base, an electric cell within the case, a float controlled switch carried by the column to occur 25 adjacent the flooding surface of the base and flexible conductor lines extending through the column and connected with and between the cell, switch and the lamp, said switch being operable to control the flow of current between the lamp and the cell, said base plate having upwardly projecting earth retaining side walls about a portion thereof to prevent shifting of earth occurring adjacent the outer sides of said side walls onto the flooding surface, said column including a lower tubular section 30 fixed to the base and projecting upwardly therefrom, an upper tubular section slidably engaged in the lower section and projecting upwardly therefrom and carrying the lamp, and manually operable lock means on the lower section to hold the upper section in fixed position relative to said lower section.
